UNITED STATES PATENT OFFICE.

WILLIAM J. GROTENHUIS, OF CHICAGO, ILLINOIS, ASSIGNOR TO BIFLEX PRODUCTS COMPANY, OF WAUKEGAN, ILLINOIS, A CORPORATION OF DELAWARE.

AUTOMOBILE BUMPER CONSTRUCTION.

Application filed September 2, 1927. Serial No. 217,033.

This invention relates to improvements in automobile bumper construction, and more particularly to a novel means and method for uniting or joining together the ends of two or more bars forming the bumper.

The object of the invention is to provide an improved form of clamping fixture or housing in which the ends of the bars to be joined are inserted and then permanently fastened together in a strong and finished manner.

A preferred embodiment of the invention is disclosed in the accompanying drawings, 15 in which

Figure 1 is a view in front elevation of one end portion of a bumper showing a typical arrangement of bars and clamping block.

Figure 2 is a top plan view of the same portion of the bumper.

Figure 3 is an enlarged detail view in vertical section taken on line 3—3 of Figure 1.

Figure 4 is a view in vertical section taken 25 on line 4—4 of Figure 6 showing one side edge of the clamping block in elevation.

Figure 5 is a view in vertical section taken 30 on line 5—5 of Figure 6 showing the opposite side edge of the block in elevation; and

Figure 6 is a detail view in vertical section taken on line 6—6 of Figure 4.

The bumper structure herein illustrated is one in which a pair of resilient steel bars 1, 35 1 spaced apart vertically form the front or impact section of the bumper, these bars being bent rearwardly and inwardly at each end to form a loop or U-shaped end portion 2. Rearwardly of the front bars 1, 1 is a 40 single rear bar 3 extending between the ends of said front bars and joined in overlapping engagement therewith by means of a clamping fixture 4, there being one of these blocks at each end of the bumper.

45 As shown in Figure 1, the front bars 1, 1 are spaced a substantial distance apart throughout the front and end portions of the bumper, but adjacent their rearward extremities they are offset edgewise toward each other, so that they assume substantially 50 edge to edge contact at the clamping fixture 4. In the shaping of these bars, notches or recesses 1^a, 1^a are also formed in their adjacent opposed edges just inwardly from

their extremities, these notches being semi-circular in shape so that when the bars are assembled, the notches register with each other and form a circular hole or opening. The rear bar 3 has a hole 3^a located a short distance inwardly from its end, and midway 55 between its edges, this hole in the rear bar registering with the hole formed by the notches 1^a, 1^a in the ends of the front bars 1, 1 when the bumper is finally assembled.

The clamping fixture 4 is a single casting 60 preferably of brass or bronze, elongated vertically, i. e., transversely of the bars, its length being slightly greater than the combined width of the two front bars 1, 1 at 65 their ends, the edges of the block being curved outwardly and its front face rounded and its surface finished to give it an ornamental appearance. Within the fixture is a hollow space included between front and rear walls 5 and 6, joined at top and bottom by end walls 7, 7. Throughout the central portion of the fixture, the rear wall 6 is offset outwardly as at 7, the amount of offset being equal to the thickness of a single bar, and its height equal to the width thereof.

At the center of the offset portion of the rear wall is a round hole 7^a in line with another hole 5^a at the center of the front wall 5. Adjacent the front wall the space is equal in height to the combined width of 80 the superimposed ends of the front bars 1, 1 and in width to the thickness of a single bar, but increased to twice that thickness by virtue of the central offset portion 7 of the rear wall. On the opposite side of the 85 fixture are vertical slots through which ends of the bars are inserted. Thus on the right side (Figure 4) a slot 9 extends substantially the full height of the block having the length and width of the superimposed bars 1, 1. Similarly, on the opposite or left side of the block (Figure 5) is a shorter vertical slot 10 offset rearwardly from the line of the longer slot and located in the 90 side of the offset portion 7. It is to be noted, 95 however, that the sides of the block opposite the two entrance slots are closed by side wall sections 11 and 12 against which the extremities of the bars abut when inserted from opposite sides. Thus the end of the rear bar 3 abuts against the end wall section 11 and the ends of the bars 1, 1 against the end wall 12, these abutments serving to

bring the bars into the proper relationship and the several holes in alignment with each other.

Thus in assembling the bumper, the ends of the bars are simply inserted into the fixture from opposite sides, thus positioning the end of the rear bar 3 just behind the ends of the front bars with equal portions of its width above and below the parting line of said front bars, and the hole 3^a in the rear bar into register with the hole formed by the edge recesses 1^a, 1^a of the front bar, and both of these holes in alignment with the holes 5^a and 7^a in the front and rear walls of the fixture.

The final operation of assembly is to drive a rivet 13 through the aligned holes, preferably from the front, and then by a suitable press or upsetting tool to rivet over the rear end, as shown in Figure 3. In this manner, the ends of the bars are permanently and rigidly fastened together forming a joint which is adequate to withstand the most severe strain to which the bumper is subjected. Moreover, the end portions of the ends of the joined bars are securely fitted into seats which prevents any looseness developing at the joint, aside from enclosing and concealing the ends in a one-piece casing free from bolts and parts which can work loose or become detached.

I claim as my invention:

1. In an automobile bumper, the combination of a plurality of bars adapted to be joined together at their ends, of a fixture cast in one piece and having openings in the sides thereof through which the ends of said bars are inserted in overlapping contact with each other, and a fastening member extending transversely through said block and the inserted portions of said bars.

2. In an automobile bumper, the combination of a plurality of bars adapted to be

joined at their ends in overlapping relation, of a clamping fixture having an internal space with openings through which the end portions of said bars are inserted from opposite sides, and abutments on the sides opposite each opening, and a rivet passing through said fixture and said bars.

3. In an automobile bumper, the combination of a plurality of bars adapted to be joined end to end in overlapping contact, of a clamping fixture having an internal space of substantially the same sectional contour as the overlapping end portions of the bars and having openings in opposite sides through which the same are inserted, said space being closed by walls on the side opposite said openings and against which the extremities of said bars abut, and a rivet passing through the front and rear walls of said block and through registering holes in said bars.

4. A clamping fixture for the purpose described consisting of a metallic fitting cast in one piece and having an internal space extending laterally thereof and openings in opposite sides thereof through which the ends of bars to be joined together are inserted for overlapping contact within said fixture, and a fastening member extending through said fixture and the enclosed portions of said bars.

5. The combination of a plurality of bars adapted to be joined at their ends in overlapping relation, of a clamping fixture having an internal space with openings through which the end portions of said bars are inserted from opposite sides, said bars having holes adapted to register with each other and with aligned holes through said block, and a rivet passing through said holes.

Signed at Waukegan, Ill., this 19 day of August, 1927.

WILLIAM J. GROTEHUIS.
